ELASTIC BRAID MADE OF BOTH DULL AND BRIGHT THREADS

Max Semmel, Yonkers, N.Y., assignor to Allied Elastic Braid Corporation, New York, N.Y., a corporation of New York

Filed Apr. 8, 1958, Ser. No. 727,084

3 Claims. (Cl. 87—2)

This invention relates to braid, and more particularly to elastic braid made of rayon.

The primary object of the present invention is to generally improve flat elastic rayon braid.

Such braid has heretofore been made for the most part out of bright rayon. However, with the increasing use of dull rayon for ladies' undergarments or the like, there has been a demand for elastic braid made of dull rayon. This has introduced a problem in greatly increasing the percentage of rejects of the finished elastic braid, particularly when made in white or very light colors, because of the presence of dark specks, apparently dirty or dark lint. I have found that whereas such specks did not adhere to the bright rayon during the braiding operation, they do tend to adhere to the dull rayon threads. These specks appear in the finished braid, and lead to rejects.

Accordingly, the main object of the present invention is to improve flat elastic braid made of dull rayon, with a view to minimizing the problem of such rejects. I have found that the introduction of some strands of bright rayon, although white or of the same light color as the dull strands, slightly breaks up the otherwise uniform surface of the braid, and gives it a slightly changed appearance against which the aforesaid specks of lint are not nearly as noticeable. Actual experience has shown that when the dull surface thus is spotted with bright threads, there is an effect presumably caused by difference in light reflection, which makes the heretofore troublesome specks relatively unnoticeable.

To accomplish the foregoing general object, and other more specific objects which will hereinafter appear, my invention resides in the elastic braid elements and their relation one to another, as are hereinafter more particularly described in the following specification. The specification is accompanied by a drawing, in which—

Fig. 1 shows a fragment of flat elastic braid made of dull rayon and having some specks of trapped lint;

Fig. 2 is a similar fragmentary and schematic view of a piece of flat elastic braid, in which the dull rayon strands are interspersed with some bright rayon strands; and

Fig. 3 is a perspective view of a braiding machine.

A braid is formed by crossing a number of strands diagonally in such a way that each strand passes alternately over and under one or more of the others. In a regular braid, each strand passes alternately over and under two of the opposite strands, and the braid shows two complete double ribs or lines of herring-bone shape.

A braiding machine is shown in Fig. 3, but not in detail because the construction may be standard. Such machines are constructed with two circular horizontal plates between which a train of gears operates. These plates are within frame ring 12. The gears have flanges or horns at the top which engage the bottom end of the bobbin carriers 14 on which the yarn is held. The upper of the two plates is formed with a serpentine path to guide the

2

bobbin carriers. These carry the bobbins of yarn, and provide suitable tension. The serpentine paths cause the meshing of the stands. The braid appears at 16, and is turned sideward at 18, and delivered into a bin at 20.

5 Flat elastic braid is made by passing a rubber thread under tension through the center of each horn gear of the braiding machine as the braid is being formed. The threads are transferred in suitable fixtures for controlling the tension evenly. Individual tensions for each rubber thread may be used. These extra parts have been omitted in Fig. 3, because they may be standard, and are not part of the present invention.

Referring now to Fig. 1, the flat elastic braid 32 has longitudinal threads 34 which are made of rubber or any equivalent material having the elastic properties of rubber. These are completely concealed within diagonally braided strands of inelastic thread, specifically dull rayon. The strands here assumed to all be white, or of the same light or pastel color, that is, the braid as heretofore made presents a light monotone appearance. A few bits or specks of dark lint are shown trapped in the braid at 36, 38, and 40.

Such specks have proved extremely troublesome since the advent of elastic braid made of dull rayon, in contradistinction to earlier braid made of bright rayon. It seems that specks of dirt or lint tend to adhere to the dull rayon strands during the braiding operation to a much greater extent than was the case with the bright rayon, presumably because of the harder, shinier surface of the latter. These specks have caused considerable loss to the manufacturer because of rejection of quantities of finished flat elastic braid by the purchaser, say a manufacturer of undergarments.

Referring now to Fig. 2, the braid there shown is similarly a flat elastic braid 42 having parallel longitudinal strands 44 of rubber or equivalent elastic material. The rubber strands are concealed within diagonally braided strands, most of which are made of dull rayon indicated at 46. However, some strands of bright rayon are interspersed, as indicated at 48. These result in tiny islands or areas which are glossy and reflect light in different fashion from the dull strands, even though all have the same color.

With this construction it is found that the presence of specks of lint is not nearly as noticeable, and that a degree of imperfection which would lead to rejection in the case of the braid shown in Fig. 1, is readily accepted without rejection in the case of the braid shown in Fig. 2. Apparently the few strands of bright rayon give the surface a slightly broken or non-uniform appearance when viewed overall, and this helps conceal the presence of dirt or lint caught by the strands during the braiding operation.

To accomplish this result, it is merely necessary to replace some of the spools of dull rayon with spools of bright rayon in the flat braiding machine shown in Fig. 3.

In the particular case here shown, seven strands of dull rayon are followed by two of bright rayon, or, in respect to those strands extending diagonally in the other direction six strands of dull rayon are followed by two strands of bright rayon. Of course, the difference in area is much greater, as it depends on the product or multiplication.

The dull and the bright rayon are preferably of the same denier. For example, if the dull strands are of 300 denier, the bright should be the same, but if the dull are of 450 denier, the bright should be of 450 denier.

The particular braiding machine here shown is a conventional machine manufactured by New England Butt Co. at Providence, R.I. In Fig. 3 the supply reels for the elastic thread have been omitted in order not to unnecessarily complicate the drawing.

In respect to Fig. 2 of the drawing it will be understood that the shading of threads 48 does not mean that they are darker threads. It is intended merely to show the highlights which are indicative of the gloss or shine of the threads 48.

It is believed that the construction and method of making my improved flat elastic braid, as well as the advantage thereof, will be apparent from the foregoing detailed description. It will also be apparent that while I have shown and described my invention in a preferred form, changes may be made without departing from the scope of the invention as sought to be defined in the following claims.

I claim:

1. A flat elastic braid having longitudinal elastic threads concealed within diagonally braided strands of inelastic thread, said strands all having the same color, most of said strands having a dull finish but some of said strands having a bright finish, thereby giving the surface of the flat braid a slightly broken or non-uniform appearance which helps conceal the presence of dirt or lint caught during the braiding operation.

2. A flat elastic braid having longitudinal elastic threads concealed within diagonally braided strands of rayon

thread, said strands all having the same color, most of said strands being a dull rayon, but some of said strands being a bright rayon, thereby giving the surface of the flat braid a slightly broken or non-uniform appearance which helps conceal the presence of dirt or lint caught during the braiding operation.

3. A flat braid having diagonally braided strands of rayon thread, said strands all having the same color, most of said strands being a dull rayon, but some of said strands being a bright rayon, thereby giving the surface of the flat braid a slightly broken or non-uniform appearance which helps conceal the presence of dirt or lint caught during the braiding operation.
